CLAIM

The ornamental design for a computer device support platform as shown and described.

DESCRIPTION

FIG. 1 is a front perspective view of a computer device support platform showing our new design;

FIG. 2 is a front elevational view thereof;

FIG. 3 is a left side elevational view thereof, the right side being a mirror image;

FIG. 4 is a rear elevational view thereof;

FIG. 5 is top plan view thereof; and,

FIG. 6 is a bottom plan view thereof; and,

FIG. 7 is a front perspective view of the computer device support platform shown in FIGS. 1-6 together with environment shown in broken lines.

The broken lines in the drawings illustrate portions of the computer device platform that form no part of the claimed design. The additional broken lines in FIG. 7 illustrate environment and form no part of the claimed design.

1 Claim, 5 Drawing Sheets
